A. D. ALEXANDER.
VICE FOR HOLDING PISTONS AND CAPS.
APPLICATION FILED AUG. 5, 1919.

1,372,665.

Patented Mar. 29, 1921.

UNITED STATES PATENT OFFICE.

ALBERT D. ALEXANDER, OF FREDERICKSBURG, VIRGINIA.

VICE FOR HOLDING PISTONS AND CAPS.

1,372,665.

Specification of Letters Patent. Patented Mar. 29, 1921.

Application filed August 5, 1919. Serial No. 315,405.

To all whom it may concern:

Be it known that I, ALBERT D. ALEXANDER, a citizen of the United States, residing at Fredericksburg, in the county of Spotsylvania and State of Virginia, have invented certain new and useful Improvements in Vises for Holding Pistons and Caps, of which the following is a specification.

My invention relates to a clamping or holding device in the nature of a vise, for use in holding pistons and also caps when it is desired to operate upon the same, such as filing, cleaning, or otherwise, as desired.

The object of the invention is to so construct the same, that it will be durable, strong, may be easily and cheaply manufactured, and will be simple and efficient in operation.

With these and other objects in view, my invention consists of receiving means for the piston or caps, as desired, which I have illustrated in the claims and described in the specification.

In the drawings forming a part of the specification and in which like symbols of reference represent corresponding parts in the several views:

Figure 1 is a perspective view of my clamp or vise, showing the piston in dotted lines on the same;

Fig. 2 is a plan view of the device; and,

Fig. 3 is a front view of the vise, showing a cap in dotted lines on the same.

The numerals 1 and 2 represent the portions of the vise forming its base; 3 perforations formed in the same for the purpose of connecting it to a support; 4 is the ring for clamping the piston, or article to be operated upon, the same being formed integral with the portions 1 and 2; and 5 shows the opening or division between the sections to permit contraction or compression of the same.

6 is a screw connected to the part 1 of the vise and extending through a bearing 16 in part 2 of the same; and 7 is a screw cap on the screw for operating in connection with the same. 8 is a perforation in the cap, and

9 a bar in the same, by means of which the cap may be revolved and the vise contracted to grip the article being operated upon. 10 50 represents the piston being operated upon.

11 are studs rising from the sections 1 and 2, and having reduced portions 12 and 13, the object being to receive and hold a cap or similar article 14, as shown in Fig. 3, when 55 it is necessary to file or otherwise treat the same. In the base of the clamping ring 4 is an enlargement 15, forming a rest for the article being operated upon.

Thus it will be seen that a piston may be 60 placed within the ring, as shown; or a cap placed on the studs, and by the simple manipulation of the screw-cap 7 may be securely and tightly gripped, and any work 65 upon the same be done with ease and effect.

Having now fully described my invention, what I claim as new, and desire to secure by Letters-Patent, is:—

1. A device of the character described, 70 consisting of a ring having free ends terminating in integral base portions, a screw connected to one section of the base portion, a bearing in the other base portion in which the screw operates, and a screw-cap on the screw for compressing the ring and base 75 parts.

2. In a vise, an annulus to receive a piston and studs to receive a cap, said vise having free ends, and means to contract said ends to clamp the articles operated upon. 80

3. A vise, consisting of an annulus having an angular base portion connected to the same, said base portion being divided, perforations in the base portion to connect it to a support, and a screw in the base portion 85 for contracting and holding the said sections.

4. A vise, consisting of portions forming a ring to receive an article and studs to receive a cap, a screw extending through the sections, and means for operating the screw to contract or expand the vise. 90

In testimony whereof I affix my signature.

ALBERT D. ALEXANDER.
